UNITED STATES PATENT OFFICE.

JACOB P. WEIS, OF ANDERSON, INDIANA.

FURNACE.

SPECIFICATION forming part of Letters Patent No. 530,869, dated December 11, 1894.

Application filed May 29, 1894. Serial No. 512,834. (No model.)

To all whom it may concern.

Be it known that I, JACOB P. WEIS, a citizen of the United States, and a resident of Anderson, in the county of Madison and State of Indiana, have invented certain new and useful Improvements in Furnaces; and I do declare the following to be a full, clear, and exact description of the invention, such as will enable others skilled in the art to which it applies to make and use the same, reference being had to the accompanying drawings, and to letters of reference marked thereon, which form a part of this specification.

Figure 1 of the drawings is a vertical longitudinal section through furnace. Fig. 2 is a section on line $x-x$, Fig. 1.

This invention has relation to certain new and useful improvements in gas and hot air furnaces, and it consists in the novel construction and combination of parts, all as hereinafter described, and pointed out in the appended claim.

The object of the invention is to provide a furnace adapted to the use of natural, or other gas, combined with hot air as a fuel.

Referring to the accompanying drawings, the letter A designates the bed of the furnace upon which are erected the side and end walls B.

C is a cold air chamber, corresponding to the ash pit in ordinary furnaces. The roof of this chamber is formed by a horizontal wall D, usually of brick, supported upon iron grates or bars a, said wall also forming the bottom of a heating or hot air chamber, which is divided into a series of longitudinal flues E. The top wall E' of this chamber and of the flues is a sheet metal plate which also forms the bottom of a combustion chamber F.

The wall D does not extend quite back to the vertical bridge wall G, but terminates sufficiently forward thereof to form a transverse opening or passage c through which the air from the chamber C rises and passes into the flues E. The space back of the cold air and the heating chamber is filled in solid, and covered with brick, which rise a little higher than the floor E' of the combustion chamber, forming a chamber G' through which the

flames and gases of combustion pass back underneath the boiler H to the rear, and thence into the boiler flues.

I designates the gas supply pipe, which feeds the gas into a transverse pipe or receiver J in the upper forward portion of the cold air chamber. From this pipe or receiver J the gas passes into a series of short burner and mixer pipes or branches K, which discharge into the forward portion of the combustion chamber. These pipes or branches are provided with any well known or suitable device for mixing with the gas, previous to combustion, the heated air from the flues E, thus greatly intensifying and increasing the combustion.

L L designate the doors to the cold air chamber, and M M the doors to the combustion chamber. These doors may be provided with any suitable form of dampers or drafts to regulate the combustion.

Having thus described my invention, what I claim as new, and desire to secure by Letters Patent, is—

In a furnace, the combination with the bed and the vertical walls thereof, of the horizontal wall D, forming a cold air chamber C between said wall and the bed, a series of longitudinal partitions above said wall D, forming a series of flues E, which communicate at their rear ends with said cold air chamber by a vertical passage c between the rear end of the wall D and a bridge wall G, a wall E' forming the top of said flues E, and the bottom of a combustion chamber F, a transverse gas receiving pipe in the forward portion of the chamber C, a series of burners extending from said pipe into the forward portion of the combustion chamber, and a gas and air mixer on each of said burner pipes in the forward portion of each of said flues E, and receiving the hot air therefrom, substantially as specified.

In testimony whereof I affix my signature in presence of two witnesses.

JACOB P. WEIS.
